UNITED STATES PATENT OFFICE.

WILLIAM HERBERT ROUSSEL, OF SAN FRANCISCO, CALIFORNIA.

PALM GRIP.

Application filed September 5, 1923. Serial No. 661,121.

To all whom it may concern:

Be it known that I, WILLIAM H. ROUSSEL, a citizen of the United States, and a resident of San Francisco, in the county of San Francisco and State of California, have invented a new and Improved Palm Grip, of which the following is a full, clear, and exact description.

The prime object of the present invention is to provide, as what is thought to be a new article of manufacture, a device to be worn on the hand somewhat like a glove or, preferably, fingerless mit, and to be utilized by handlers and particularly lifters of sacks or similar containers of grain, coffee or other material. Inasmuch as the underlying thought of the invention is to provide a plurality of spaced teeth or prongs, preferably by establishing the latter as beards or similar integral projections from a metal plate or other suitable member, and in turn to provide a flexible means for mounting this plate or equivalent and adjustably securable to the hand, the new article of the present invention may conveniently be called a grab-glove.

The flexible means just referred to may be shawl-like, that is, to be wrapped around the portion of the hand beyond the knuckle joints of the fingers and thus adjustably secured by a gauntlet strap or the like, or may be permanently sleeve-like in character; but preferably designed in such a way, when limited to a sheathing of the hand beyond the finger roots, that the weight of the packages or sacks is taken up by the wrist. The glove is preferably without fingers, so as to allow the free use of the latter; but, on the other hand, the glove is preferably so designed, as by providing, in addition to the main part of the glove, which may be termed the palm-sleeve, a lesser sleeve for the whole or part of the thumb; thus to furnish a means for preventing shifting of the glove around the hand.

Thus the present invention provides a grab-glove, whether covering only part or parts of the hand or the whole thereof, which glove has securely mounted on the portion thereof to overlie the palm a plurality of grabbing or biting teeth or prongs, directly or indirectly mounted on such portion of the glove, preferably as integral portions, as aforesaid, of a plate mounted by the glove. This plate, conveniently of steel or brass, is preferably riveted to the glove.

The invention will be best understood from a consideration of the following detailed description when taken in connection with the accompanying drawing forming 60 part of this specification; with the understanding, however, that such drawing illustrates, merely by way of example, one possible embodiment of the invention, and that the invention is not confined to any strict 65 conformity with the showing in the drawing, but may be changed and modified so long as such changes and modifications mark no material departure from the salient features of the invention as expressed in the 70 appended claim.

In said drawing,

Fig. 1 shows a grab-glove of the present invention as applied to a hand, looking toward the palm of the hand;

Fig. 2 is a transverse section through the glove, taken on the line 2—2 of Fig. 1;

Fig. 3 shows the glove as viewed in Fig. 1 but removed from the hand and opened out; and

Fig. 4 is an enlarged fragmentary detail, taken on the line 4—4 of Fig. 3.

As will be noted, the glove illustrated is of the aforesaid shawl type and comprises a main strap-like sheet 5, of leather, canvas or other suitable material, carefully patterned and cut to afford mounting, as by the welting or seaming indicated at 6, a truncated thumb stall or thumb sleeve 7 also of leather, canvas or the like.

In the present case, the grab-proper presents a plurality of spaced rows of spaced teeth or prongs 8. These grab-teeth are beards, that is, portions of the metal of a fairly thin plate 9 punched or chiselled up out of the face of the plate to be exposed. All the teeth or prongs 8 of course extend similarly and so that each is slightly inclined to the plane of the plate and toward the wrist when the entire device is mounted on the hand. Plate 9 is rigidly secured to the glove at suitable points, as by means of rivets 10.

The embodiment of the invention illustrated being as aforesaid of the shawl type, the terminal portions of sheet 5 marked 5^a and 5^b are intended to be overlapped at the back of the hand. A gauntlet strap 11 is stitched as at 12 to portion 5^a of the sheet and carries a slider device 13 mounting one of the elements 14 of a familiar glove-fastener the other element 15 of which is se-

cured to the free end of strap 11. The opposite end portion 5^b of sheet 5 carries an eye-loop 16, as by means of a short strap-loop 17 stitched to sheet 5 as at 18. When the new device is worn on the hand, of course, the thumb is passed through sleeve 7, and sheet 5 is wrapped around the hand so that, with sheet-portion 5^a overlapping sheet-portion 5^b as shown in Fig. 2, the strap 11 may be drawn under through eye-loop 16, then reversely folded to align the glove-fastener elements 14 and 15, and then such elements are snapped together to set the sheet 5 securely to corset the hand and dispose plate 9 as shown in Fig. 1.

In operation, the new grab-glove as worn by a person handling and lifting sacks and packages (and he may wear such a glove on one or both hands), presents numerous teeth or prongs so inclined that the points thereof securely engage the fibres of the material of which the sacks or packages are made, and permit such a sack or package, especially when filled with grain, coffee or a similar mass of small particles, to be handled, as dragged or lifted, with absolute assurance that slippage of the sack or package will never occur. During such handling of the sacks or the like, the fingers are free

for use in facilitating the work, for repositioning the teeth or prongs when required, and for easily releasing the grab-glove or gloves and the hand or hands thereby sheathed. The hands are thus easily released, when the teeth are not long enough to enter deeply the sack or package material. And there is no danger of tearing or otherwise injuring such material, as the teeth take numerous holds.

I claim:

A device of the character described, comprising a strap-like member having a truncated thumb sleeve and of a length to extend around the hand with its inner longitudinal edge overlying the wrist and its ends overlapping one another, means for securing the ends in overlapping relation, and a plate secured to the strap-like member intermediate of its ends and adjacent to the inner longitudinal edge of the member so as to partly overlie the wrist, said plate being provided with short prongs or teeth punched out of the plate and distributed over its whole surface, the prongs or teeth being inclined to the plane of the plate and in direction of the inner edge of the said member.

WILLIAM HERBERT ROUSSEL.
